(57) CLAIM

The ornamental design for a mixing bowl, as shown and described.

DESCRIPTION

FIG. 1 is a front perspective view of a mixing bowl showing my new design;

FIG. 2 is a side elevation view of the mixing bowl; the opposite of which is an identical mirror image;

FIG. 3 is a top plan view of the mixing bowl;

FIG. 4 is a front elevational view of the mixing bowl;

FIG. 5 is a bottom plan view of the mixing bowl; and,

FIG. 6 is a cross sectional view of the mixing bowl taken along line 6—6 of FIG. 4.
